CHARLES A. SMITH, OF PHILADELPHIA, PENNSYLVANIA, ASSIGNOR TO BLAIDSDELL
PAPER PENCIL COMPANY, A CORPORATION OF PENNSYLVANIA.

PENCIL.

1,233,815.

Specification of Letters Patent. Patented July 17, 1917.

Application filed November 6, 1914. Serial No. 870,692.

To all whom it may concern:

Be it known that I, CHARLES A. SMITH, a citizen of the United States, and resident of Philadelphia, county of Philadelphia, 5 and State of Pennsylvania, have invented an Improvement in Pencils, of which the following is a specification.

The object of my invention is to provide a construction of pencil wherein successive 10 strips or sections of the wrapper expose successive portions of the lead or crayon, and in which, moreover, the act of removal of one strip or section of the wrapper provides an exposed free edge upon the next adjacent 15 strip or section of the wrapper under which the nail of the finger may be readily inserted for freeing the outermost portion of said next adjacent strip or section to cause the ready removal thereof.

20 In paper pencils as heretofore constructed, the wrappers have been so formed and tightly wound that there have been no sufficiently exposed edges by which the starting 25 of the detachment of the strip or section to be removed could be accomplished, and it frequently happens that it was practically impossible for the fingers to liberate the strip unaided by a knife, pin or other metallic instrument; and it is particularly my object 30 to overcome this difficulty in paper pencils whereby they may with facility be re-pointed.

My invention consists of certain improvements in pencils in which the body portion 35 is formed of a spirally wound wrapper of paper or other sheet material so constructed that successive portions of the wrapper may be unwound and removed at will and in doing so bring into exposed condition a free 40 edge upon the wrapper whereby the same may be readily engaged with the finger nail for removing the strips, said construction being fully described hereinafter and more particularly defined in the claim.

45 In the drawings: Figure 1 represents a wrapper for a pencil embodying my invention; Fig. 2 represents a side elevation of a portion of a pencil showing the preferred embodiment of my invention.

50 Similar numerals of reference indicate corresponding parts.

1 designates a sheet of paper or like suitable material adapted to form the body of a pencil when wrapped about the lead in the 55 proper manner. In order to build up the

said body it is desirable to wind the sheet of material 1 in spiral form about the lead and for this purpose the opposite side edges 2 of the sheet 1 are cut on the bias, as will readily be understood. The sheet 1 is preferably 60 scored transversely as shown at 3 to form a plurality of parallel strips 4 which extend from one side of the sheet to the other, the said scorings 3 serving to weaken the material so that the strips may be readily 65 detached as desired. In the assembled article, therefore, as each strip is unwound and detached a new portion of the lead 5 is exposed for use so that the pencil is resharpened without the use of a knife or like implement. In the preferred embodiment of 70 my invention I have provided a plurality of slots or apertures 6 arranged in two rows, the slots of one row being staggered with respect to the slots of the other row and 75 each aperture being positioned to intersect one of the transverse scorings 3. Thus, as shown in Fig. 1, one row is formed by apertures which intersect alternate score lines while the opposite row is similarly formed 80 by its apertures intersecting the remaining alternate score lines.

It will further be noted that the apertures of one row are so dimensioned and arranged with respect to adjacent apertures of the 85 next row that any tearing of the strip, transverse to the axis of the pencil, will intersect one of the apertures and thus shift the tear to the score 3 by which the particular strip is attached to the next strip. In 90 other words, each aperture is of sufficient length to lie in the path of a transverse tear starting from the adjacent aperture so that under substantially all conditions the detaching of one strip insures a clean tear 95 along the score line and leaves a free edge on the next adjacent strip to permit it to be readily taken hold of and detached.

In connection with these apertures it will be noted that as each strip is torn off or 100 removed from the body it leaves the remaining strip with an open ended aperture forming a distinct angular corner 7 which forms a positive and effective means for taking hold of the strip to initially start the 105 unwrapping action.

The operation of re-pointing the pencil will be apparent from Fig. 2 and takes place as follows.—The finger nail may be used to readily pick the corner 7 loose so 110

that it can be gripped by the fingers, after which the strip is unwound by tearing it transversely to the adjacent aperture, and at this point the tear is transferred to the 5 score line so that the strip is separated along the definite line provided and leaves a clean cut free edge on the next strip. In view of the spiral wind the detaching of the strip exposes a new portion of the lead 10 and the pencil is ready for use.

In describing the detaching of the strips from the body of the material I have referred to the free edge left on one strip by the removal of another strip, and it will be 15 noted that this is possible in view of the fact that the adhesive or glue 8 which is employed to secure the end of the strip to the body does not extend over the portion of the material in which the apertures are located. It will thus be evident that, in building up the body by wrapping the sheet forming the strips around the lead, there is no adhesive between the contacting surfaces 20 of the strips adjacent the portion where the apertures are made, and therefore the lower edge of each strip is entirely free and may be readily separated from the underlying 25 portions of the material.

It will be understood from the foregoing 30 description, taken in connection with the drawings, that in tearing off a strip or section of the body of the pencil the tear started in the exposed free edge or corner 7 of the wrapper will produce a transverse tear which will extend into the lower edge 35 of the next adjacent aperture, thereby exposing a free edge or corner on the next adjacent strip or section, and a continuance 40 of the tear will extend along the scored line 3 opening from this second aperture into which the tear is extended. In the case of Fig. 2 it is manifest that the tear will ex-

tend from the top of one aperture to the bottom of the next and will thence continue on to the scored line 3.

I have shown the preferred form of my invention and while the construction shown is preferred I do not restrict myself to the minor details except as they are set forth in the claim as these may be modified without departing from the spirit of the invention.

Having now described my invention, what I claim as new and desire to protect by Letters Patent is:—

In a lead pencil device of the character stated, a body formed of a sheet of material wound spirally about the lead and retained in wrapped condition, said sheet having a plurality of parallel scored lines 60 transversely to the length of the pencil, and also provided adjacent to its outer edge with a plurality of apertures arranged along the length of the pencil in two parallel rows, each scored line crossed by a different aperture and successive scored lines crossed by apertures alternately of each parallel row, whereby an aperture from each row will extend in opposite directions from adjacent scored lines into the same transverse 65 strip of material between the scored lines, the construction being such that by tearing the strip transversely to the axis of the pencil from the upper end of any aperture of one row, such tear will intersect the aperture of the other row and through it continue along the scored line extending from 70 said aperture.

In testimony of which invention, I hereunto set my hand.

CHARLES A. SMITH.
